Attorney

UNITED STATES PATENT OFFICE.

LEWIS BISHOP, OF ARCADIA, FLORIDA.

AXLE STRAIGHTENER.

Application filed February 20, 1925. Serial No. 10,585.

This invention relates to an axle or rod straightener.

The object of the invention is to provide simple, strong and efficient means for straightening bent axles, frames, rods and other articles of this character and whereby such may be accomplished with a minimum amount of exertion and yet effectively straighten the bent member.

10 With the foregoing and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

20 In the accompanying drawings:—

Figure 1 represents a side elevation of a straightener constructed in accordance with this invention with the parts shown arranged for straightening a rod bent intermediate its ends, the rod being illustrated in dotted lines;

Fig. 2 is a similar view showing the parts arranged for straightening a rod or axle bent at the ends;

30 Fig. 3 is a top plan view of the device with the parts arranged as shown in Fig. 2; and

Fig. 4 is an end elevation of the device with the parts shown arranged as illustrated in Fig. 1.

In the embodiment illustrated the straightener constituting this invention comprises two strong metal bars 1 and 2 arranged in parallel relation and held spaced apart by bolts or rods 3 extended through the ends thereof and carrying between said bars spacers 4. These spacers 4 are shown in the form of sleeves mounted on the bolts 3.

Two swiveled screws 5 and 10 are mounted between the bars 1 and 2 and are designed to carry the portable hooks 20 and 21 which support the rods or axles A to be straightened. These screws 5 and 10 as shown have bifurcated lower ends between the furcations 6 of which are arranged the shanks 22 of the hooks, said shanks being hingedly

mounted by bolts 7 passing through the furcations and the shanks. The screws are exactly alike and consequently one only will be described in detail.

55 Nuts 8 are mounted on the upper ends of the screws 5 and 10 and have washers 9 arranged between them and the upper edges of the bars 1 and 2. Similar washers 11 are disposed between the lower edges 60 of the bars and the bifurcated ends of the screws as is shown clearly in Fig. 2.

These hook carrying screws 5 and 10 are removably and adjustably mounted between the bars so that they may be positioned at 65 any desired point for use in connection with axles or rods bent at different places.

Pressure screws 12 and 13 are also adjustably mounted between the bars 1 and 2 and each is equipped with a nut 14 having 70 threaded engagement with the screw below the bars. The pressure screws 12 and 13 are equipped at their upper ends with heads 15 having openings 16 extending transversely through them to receive rods or 75 wrenches for turning the screws to exert pressure on the axle or rod to be straightened. These pressure screws are equipped at their lower ends with rod engaging feet 17 which are designed to bear on the bent portion of the axle or rod to be straightened as shown clearly in Fig. 1.

80 In the use of this device when an axle or rod A is bent intermediate its ends the hooks to support it are located at the ends 85 of the bars 1 and 2 as shown in Fig. 1 and the pressure screws are positioned between these supporting hooks over the part of the axle to be straightened. When the parts are so positioned obviously the screwing of 90 the pressure screws downwardly will cause them to exert pressure on the axle at the bent portion and straighten it up.

95 Obviously these hooks and pressure screws may be positioned to meet the requirements of the work to be straightened and should any member become broken or injured it may be readily removed and replaced.

I claim:—

100 In a device of the character described, a body portion including spaced bars, bolts positioned between the bars, said bolts hav-

ing bifurcated ends, hook members pivotally mounted between the furcations, washers secured on the bolts and adapted to engage one side of the body portion, washers on the 5 opposite ends of the bolts and adapted to engage the opposite side of the body portion, nuts on the bolts for clamping the washers

into close engagement with the body portion, and means at the ends of the body portion for engaging the article under operation.

10

In testimony that I claim the foregoing as my own, I have hereto affixed my signature.

LEWIS BISHOP.
